US0D1015074S

(12) **United States Design Patent** (10) **Patent No.:** **US D1,015,074 S**
(45) **Date of Patent:** **** Feb. 20, 2024**

(54) **DRINKING BOTTLE**

(71) Applicant: **PI-Design AG**, Triengen (CH)

(72) Inventor: **Jorgen Bodum**, Meggen (CH)

(73) Assignee: **PI-DESIGN AG**, Triengen (CH)

(**) Term: **15 Years**

(21) Appl. No.: **29/805,982**

(22) Filed: **Aug. 31, 2021**

(30) **Foreign Application Priority Data**

Mar. 4, 2021 (WO) WIPO102466

(51) **LOC (14) Cl.** **07-01**

(52) **U.S. Cl.**

USPC **D7/511**; D7/510; D7/532

(58) **Field of Classification Search**

USPC D7/507, 509, 510, 511, 514, 523, 532, D7/533, 535, 536, 392.1, 396.1, 396.2, D7/608; D3/202; D9/435, 443, 446, 449

(57) **CLAIM**

The ornamental design for a drinking bottle, as shown and described.

DESCRIPTION

FIG. 1 is a perspective view of a drinking bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the drinking bottle that form no part of the claimed design.

1 Claim, 7 Drawing Sheets
